ADJUSTABLE GARMENT HANGER

Filed March 19, 1948

UNITED STATES PATENT OFFICE

2,513,484

ADJUSTABLE GARMENT HANGER

Lida B. Hensley, Yuma, Ariz., assignor of one-half to Henry J. Albert, Yuma, Ariz.

Application March 19, 1948, Serial No. 15,943

7 Claims. (Cl. 223—95)

1

This invention relates to an adjustable garment hanger especially adapted for use in supporting skirts and which is adapted to fit into the waistband portion of a skirt for supporting the skirt in an extended position to prevent wrinkling thereof and which may be quickly and easily engaged with or disengaged from skirts having waist portions of different sizes.

More particularly, it is an aim of the present invention to provide an adjustable garment hanger of extremely simple construction and which is composed of a minimum of parts.

Another object of the invention is to provide a garment hanger capable of being economically manufactured and which will be extremely efficient and durable for its intended purposes.

Various other objects and advantages of the invention will hereinafter become more fully apparent from the following description of the drawing, illustrating a presently preferred embodiment thereof, and wherein:

Figure 1 is a side elevational view, partly in section of the garment hanger;

Figure 2 is a fragmentary bottom plan view thereof;

Figure 3 is an enlarged cross sectional view taken substantially along a plane as indicated by the line 3—3 of Figure 1;

Figure 4 is a similar view taken substantially along a plane as indicated by the line 4—4 of Figure 1, and

Figure 5 is a plan view of one element of the garment hanger.

Referring more specifically to the drawing, the novel garment hanger in its entirety is designated generally 6 and comprises a body member 7, a supporting hook 8 and two corresponding extensible members, each designated generally 9.

The body member 7 is formed from an elongated strip of metal, preferably aluminum plate, which is folded longitudinally and intermediate of its side edges and the folded edge 10 of which is provided with an opening 11 for accommodating the shank 12 of the hook 8 which extends therethrough and which is provided on its shank end with an eye 13 which is disposed between the corresponding, spaced folds or plies 14 of the body member 7. Said folds or plies 14 in transverse alignment with the opening 11 are provided with external indentations or pressed in portions forming internal projections 15, as best illustrated in Figure 3, which are disposed in opposed relationship to one another and which extend into the opening of the eye 13 for connecting the hook 8 to the body member 7.

2

Each of the extensible elements 9 comprises a strand of relatively heavy gauge wire, preferably steel wire and which is relatively resilient. Each of said wire strands is bent upon itself intermediate of its ends to provide an intermediate portion having an inner substantially straight leg 16 and an outer leg 17 the lower portion of which is outwardly offset as seen at 18 adjacent the bight of the strand. The inner leg 16 merges with one terminal of the strand which is disposed at substantially a right angle thereto and which forms a substantially straight leg 19 which terminates in an eye 20. The other, likewise substantially straight terminal 21 of the strand merges with the outer leg 17 and is disposed at an obtuse angle thereto and at substantially an acute angle to the leg 19 in the normal position of the parts, as illustrated in Figure 5. Said leg 21 on its outer side and on the side thereof remote to the leg 19 is provided with longitudinally spaced notches 22, for a purpose which will hereinafter become apparent. The leg portions 19 and 21 of the two waist engaging elements 9 are adapted to slidably engage between the folds 14 of the body members 7 so that one of said elements 9 projects from each end of the body member 7 and the folds 14, adjacent their ends, are provided with indentations forming inwardly opposed protuberances 23, as best seen in Figure 4, which are disposed in opposed pairs and which are adapted to engage the legs 19 for holding the legs 19 and 21 between said protuberances 23 and the folded edge 10 and in substantially parallel relationship, as illustrated in Figure 1, so that the legs 21 will be thereby held under tension and in yieldable engagement with the inner side of the folded edge 10 of the body 7. Said folded edge 10 adjacent its ends is transversely dented to provide inwardly projecting transverse projections 24 which are substantially V-shaped in cross section, as best seen in Figure 1 for selectively engaging the notches 22 for detachably latching the waist engaging elements 9 to the body member 7. It will also be noted that the loops or eyes 20 project downwardly and are disposed to provide abutments for engagement with the protuberances 23 for limiting the extent that the waist engaging members 9 can be extended outwardly with respect to the body member 7.

From the foregoing it will be readily apparent that by grasping the portions 16, 17 of the members 9 and forcing them outwardly and upwardly with respect to one another that the legs 21 will be swung downwardly and away from the folded

edge 10 to disengage the notches 22 thereof from the projections 24 so that said extensible members 9 may be either extended or retracted with respect to the body member 7. Said extensible members 9 are initially retracted into the body member 7 so that the hanger 6 can be positioned in the waist portion of a garment, not shown, such as skirt after which, in the manner as previously described, the waist engaging elements 9 are extended until the skirt waist portion is held in an extended position therebetween and said members 9 are latched in their extended position with respect to the body 7 by selectively engaging notches 22 thereof with the projections 24. The waist portion of the skirt or other garment will be engaged by the outer leg portions 17 and the outwardly inclined portions 18 thereof will effectively function to prevent the skirt from slipping out of engagement with the members 9. The hook 8 projects upwardly from the folded edge 10 of the body 7 and is adapted to engage any suitable supporting means for suspending the hanger 6 and with the garment supported thereby.

Various modifications and changes are contemplated and may obviously be resorted to, without departing from the spirit or scope of the invention as hereinafter defined by the appended claims.

I claim as my invention:

1. An adjustable garment hanger comprising an elongated body member, a hook connected to said body member intermediate of the ends of the body member and extending upwardly therefrom, and waist engaging members projecting from each end of said body member each having an outer portion adapted to detachably engage the waist portion of a garment, said waist engaging members being extensible with respect to said body member, said body member and waist engaging members having co-acting portions forming latch means for releasably retaining said waist engaging members individually in various extended positions with respect to the body member.

2. An adjustable garment hanger comprising an elongated body member, a hook connected to said body member intermediate of the ends of the body member and extending upwardly therefrom, and waist engaging members projecting from each end of said body member each having an outer portion adapted to detachably engage the waist portion of a garment, said waist engaging members being extensible with respect to said body member, said body member comprising an elongated metal strip folded longitudinally to form a relatively deep downwardly opening channel of a width to closely engage portions of the waist engaging members.

3. An adjustable garment hanger comprising an elongated body member, a hook connected to said body member intermediate of the ends of the body member and extending upwardly therefrom, and waist engaging members projecting from each end of said body member each having an outer portion adapted to detachably engage the waist portion of a garment, said waist engaging members being extensible with respect to said body member, said body member comprising an elongated metal strip folded longitudinally to form corresponding plies, the folded edge of said strip being provided with an opening intermediate of its ends for receiving the shank portion of the hook, said hook having an eye at its shank end disposed between said plies, and said plies being indented to provide internal protuberances ex-

5 4 tending into said eye for attaching the hook to the body member.

5 4 An adjustable garment hanger comprising an elongated body member, a hook connected to said body member intermediate of the ends of the body member and extending upwardly therefrom, and waist engaging members projecting from each end of said body member each having an outer portion adapted to detachably engage the waist portion of a garment, said waist engaging members being extensible with respect to said body member, each of said waist engaging members being formed from a strand of relatively heavy gauge wire having a down turned intermediate portion disposed beyond an end of the body member and leg portions disposed in telescopic engagement with an end of the body member.

5 4 An adjustable garment hanger comprising an elongated body member, a hook connected to said body member intermediate of the ends of the body member and extending upwardly therefrom, and waist engaging members projecting from each end of said body member each having an outer portion adapted to detachably engage the waist portion of a garment, said waist engaging members being extensible with respect to said body member, said body member comprising an elongated metal strip folded longitudinally to form a narrow downwardly opening channel, each of said waist engaging members being formed from a strand of relatively heavy gauge wire having a down turned intermediate portion disposed beyond an end of the body member and leg portions disposed one above the other in telescopic engagement with an end of the body member.

5 4 An adjustable garment hanger comprising an elongated body member, a hook connected to said body member intermediate of the ends of the body member and extending upwardly therefrom, and waist engaging members projecting from each end of said body member each having an outer portion adapted to detachably engage the waist portion of a garment, said waist engaging members being extensible with respect to said body member, said body member comprising an elongated metal strip folded longitudinally to form a narrow downwardly opening channel, each of said waist engaging members being formed from a strand of relatively heavy gauge wire having a down turned intermediate portion disposed beyond an end of the body member and leg portions disposed one above the other in telescopic engagement with an end of the body member, said strip having integral inwardly projecting protuberances for engaging beneath the bottom leg portions of the extensible waist engaging elements for retaining both leg portions of each waist engaging element between one of the protuberances and the folded edge of said strip.

5 4 An adjustable garment hanger comprising an elongated body member, a hook connected to said body member intermediate of the ends of the body member and extending upwardly therefrom, and waist engaging members projecting from each end of said body member each having an outer portion adapted to detachably engage the waist portion of a garment, said waist engaging members being extensible with respect to said body member, said body member comprising an elongated metal strip folded longitudinally to form a narrow downwardly opening channel, each of said waist engaging members being formed from a strand of relatively heavy gauge wire having a down turned intermediate portion disposed beyond an end of the body member and leg por-

tions disposed one above the other in telescopic engagement with an end of the body member, said strip having integral inwardly projecting protuberances for engaging beneath the bottom leg portions of the extensible waist engaging elements for retaining both leg portions of each waist engaging element between one of the protuberances and the folded edge of said strip, said leg portions being normally spring biased away from one another, said upper leg portions being provided with spaced notches, and the folded edge of said strip being provided with an integral inwardly projecting detent adjacent each end thereof for selectively engaging the notches of the adjacent upper leg portion for releasably 15

latching said extensible waist engaging elements individually in various extended positions with respect to the body member.
